Eliphalet Nott

8192X

Letters Patent.

The Schedule referred to in these Letters Patent, and making part of same, containing a description in the words of the said Eliphalet Nott himself of his improvement in Kitchen Ranges both fixed and movable; for the purpose of facilitating the use of anthracite coal therein.

1. In combining a chamber of combustion, chiefly in nonconducting material, with a central tower for preparing and supplying fuel, called the feeder, and with two separate kettle-places one on each side thereof, the same usually lined with a nonconducting material, and extended horizontally beyond said chamber,cocking in the ends and connecting at their extremities with outlets provided by valves so that the flame can be directed in either chamber or in both at pleasure, the whole capable of being adjusted permanently in the fire-place, and called for distinction sake, the Fixed Range, or of being placed temporarily in any part of the room, called for distinction sake, the Movable Range. 2. In combining the ends of the chamber of combustion, under the overhanging kettle-places in the fixed Range, fixed tin or other reflecting iron, to be heated solely, if desired, from the bottom of the overhanging places, and the ends of the chamber of combustion.
3. In combining with each of said fixed ovens, a reflector, that is, a separate trap or other reflecting bottom so inclined as to increase the upward reflection more or less if desired. 4. In combining with each of said fixed ovens a Radiator, that is, a metallic section of iron, situated at or near the bottom of the chamber of combustion, of such size and thickness and connected with the brick or other nonconducting section of iron, as to insure the transmission of sufficient heat to the oven, for baking the bottom of the article.

8792 X

contained therein, which Radiator may be either a mere metal
plate, or a plate perforated like a honey comb, with small holes
to be filled with clay or other nonconducting material. 5. In com-
bining also, if desired, on the back of the chamber of combustion,
in said fixed range, an upward reflecting iron, that is, an iron
commencing at or near the bottom of the chamber of combustion
and rising so much above the same as to be acceptable by doors on
said chamber, for placing things on a middle plate or shelf,
at or near the level of the top of said chamber, after the manner of
the ovens in kitchen ranges already in use; but constructed of
tin or other reflecting material in place of iron and heated by
means of a Radiator, situated in the back of the chamber of com-
bustion, in connection with the bottom back and ends of the oven
itself—the whole bottom and sides being adjusted in such re-
lative angular positions, as to have the greatest practicable amount
of heat up against the shelf or middle plate aforesaid, on which
the contained articles are placed. 6. In combining with the chamber
of combustion in the Fixed Range, either a stone front, an open-
gated front, or a transparent front and reciprocating flues in
use in stone patent parlour or hall stoves. 7. In combining with
said front of whichever kind, in said fixed range, an exterior moveable
front bake oven, roaster, or other culinary instruments, into or other re-
flecting material, the same having if desired, apertures formed by holes
on the upper or under side or on both, for the admission of air when necessary
for regulating the temperature or improving the flavor; which
combination may be effected by adapting to each other the front
of said furnace and the face of said instrument with inside structure
and form, so as to make when combined, a regular fit, and by con-
necting the same by hanging the latter against the former, likewise
so as to open and shut, and ship and unship; or by providing for
connecting the same by means of rollers, ways, kitchens, hooks or any
other fixture preferred. 8. In combining with the moveable range,
removeable bake ovens, roasters or other culinary instruments
into

8792X

on tin or other reflecting materials, by hanging the same on the sides of the chamber of combustion like dooryards, or in such manner as to open and shut, and ship and unship; or by otherwise adjusting them thereto, by means of rollers, brackets, hooks or any other fixture for joining. (9) In projecting the kettle floor, in the movable range, the back in place of the ends of the chamber of combustion, if desire, and in combining therewith a fixed form of the same material, & having the same fixtures, and to be heated in the same manner, the same combined on the ends of the chamber of combustion in the fixed range aforesaid. (10) In combining with the chamber of combustion in the movable range, a close front, an open front, a plated front or a transparent front and reciprocating fire after the manner of a kettle, patent stoves aforesaid, as preferred, in dispensing with the kettle floor on one side of the central tube if desired. (11) In combining in said range, whether fixed or removable the rotary flat or reciprocating plate in any of its forms as heretofore made use of in kettle patent stoves; or in dispensing with a bottom plate altogether, and substituting (in place thereof) a mere close slide, drop or rotary floor, for emptying out residuum; the air being passed to the fire through the reciprocator aforesaid. For further information reference may be had to the drawings and explanations connected herewith.

Claims.— I claim among invocations the several improvements existing cooking ranges, set forth in the foregoing several combinations, together with the uses to which the same has been or may hereafter be applied.
